REISSUED

UNITED STATES PATENT OFFICE.

LEOPOLD AVISUS, OF CHICAGO, ILLINOIS.

PIANO-AGRAFFE.

No. 907,713.

Specification of Letters Patent.

Patented Dec. 29, 1908.

Application filed April 3, 1908. Serial No. 424,861.

To all whom it may concern:

Be it known that I, LEOPOLD AVISUS, a citizen of the United States, and a resident of Chicago, in the county of Cook and State 5 of Illinois, have invented certain new and useful Improvements in Piano-Agraffes, of which the following, when taken in connection with the drawing accompanying and forming a part hereof, is a full and complete 10 description, sufficient to enable those skilled in the art to which it pertains to understand, make, and use the same.

This invention relates to means to determine the vibrating length or portion of a 15 piano string, (or wire). And the object of the invention is to obtain a device which may be placed on the bridge of the sounding board of a piano, and also on the pin block, and no tendency to split or otherwise injure 20 the bridge or pin block will occur by such placing of such device.

A further object of the invention is to obtain a device which is cheaply constructed, easily placed in position, and not liable to 25 become loosened or moved from its position, and one from which, in case of a broken string, or wire, such string may be removed and a new one readily placed thereon and in engagement therewith.

30 A further object of the invention is to obtain a device which may be formed up from sheet metal, while at the same time means are provided to obviate all metallic ringing of the strings or wires controlled thereby.

35 I have illustrated a device embodying this invention in the drawing referred to, in which—

Figure 1 is a plan view of a portion or part 40 of a sounding board and bridge of a piano, showing also some of the pin block and strings thereof, with devices embodying my invention in position under the strings, on the bridge and on the pin block. Fig. 2 is a top plan view, on an enlarged scale, of a device 45 embodying my invention. Fig. 3 is a vertical sectional view on line 3—3 of Fig. 2, viewed in the direction indicated by the arrows. Fig. 4 is a top plan view of a sheet metal blank, from which the metallic part 50 of the device illustrated in Figs. 2 and 3, is formed up. Fig. 5 is a vertical sectional view, on line 5—5 of Fig. 6, viewed in the

direction indicated by the arrows, of a modification of the construction illustrated in Figs. 2, 3 and 4. Fig. 6 is a top plan view 55 of the modification shown in vertical section in Fig. 5. Fig. 7 is a plan view of a sheet metal blank, from which the modification illustrated in Figs. 5 and 6, is formed up. Figs. 8 and 9 are, respectively, perspectives 60 of a wooden or composition metal block forming elements in the construction illustrated in Figs. 2, 3 and 4, and Fig. 10 is a perspective of a steel pin or rod forming an element in the construction illustrated in Figs. 65 2, 3 and 4.

A reference letter applied to designate a given part is used to indicate such part throughout the several figures of the drawing, wherever the same may appear.

A is the frame of the piano, B the sounding board, C the bridge, D the pin block, and d the hitch pin plate. E, is a device embodying my invention: and F is a modification of the construction of the device E.

The construction of the devices E are well illustrated in Figs. 2, 3 and 4 of the drawing, and such device consists of a sheet metal blank, (see Fig. 4), bent or formed up to obtain body portion G, side wings or 80 ears g, g, and the end wing or ear g', with recesses hereinafter specifically described, therein. The side wings or ears g, g, are bent up at substantially right angles to the body portion G, on the lines H, H, and the wing or ear g' is bent upward on line h into substantially the position thereof illustrated in Figs. 2 and 3. Ear g' is provided with notches h', h', in which notches the strings or wires of the piano lie when the device is 90 in use, to keep such strings in suitable relative position. The body portion G of the blank is provided with the hole I, through which screw J extends to attach the device in position: and is also provided 95 with the punched out triangular part K, to prevent movement around such screw. The side wings g, g, are provided with the recesses L, M, and N. When such ears are bent up into position, as described, the 100 wooden or composition metal block or bar O, (see Fig. 8), may be put into position in recesses L, L: the wooden or composition metal block or bar P, (see Fig. 9), may be

placed in position in recesses M, M: and when the device is put in position for use and the strings X, X, are drawn over the device, such strings will rest on such blocks or bars 5 O, P.

The pin or rod Q, (see Fig. 10), preferably a steel pin, may be forced into place in recesses N, N, after the strings X are in place over the blocks or bars O, P.

10 The several recesses L, M and N, are so associated relative to each other, that when the blocks or bars O, P, and the rod or pin Q are put into position, as above described, and as is well illustrated in Fig. 3 of the drawing, the rod or pin Q forces the strings down between the blocks or bars O, P, deflecting them from a horizontal plane, thus insuring a firm bearing or resting of the string on such blocks or bars O, P.

15 20 In forming up this device the body portion G of the blank is preferably slightly concaved on the under side thereof, as is shown at R, Fig. 3, so that tension on the screw J will at all times be maintained.

25 25 The screw J and the point K are the only means by which the device is attached to the bridge C and no danger of splitting the bridge is incurred thereby.

The modification illustrated in Figs. 5, 30 6 and 7, obviates the use of the blocks or bars O and P, and retains the recesses N, N, and pin or rod Q. In this modification one end of the body portion G of the blank is prolonged, as at G', Fig. 7, and such end 35 is bent up on the lines H', H', to form bridge S, illustrated in Figs. 5 and 6. And such bridge S performs the same functions as the block or bar O. This modification, (illustrated in Figs. 5, 6 and 7) may be used 40 on bridge C, when it is considered that metallic sound produced thereby in the vibration of the strings engaging therewith is not objectionable. Where it is preferred to have the strings rest or bear on wood or 45 composition metal, (as Babbitt or type metal), on the bridge, the modification illustrated in Figs. 5, 6 and 7 is not used: but in place thereof the device illustrated in Figs. 2, 3 and 4 is employed.

50 50 In the modification illustrated in Figs. 5, 6 and 7, the wings or ears g, g, are retained, slightly changed in shape by the omission of recesses L, and M, and the end wing or ear g', provided with notches h', h', is retained: and such wings or ears are formed up into substantially the position illustrated in Figs. 5 and 6 of the drawings, and the strings rest in such notches, to bear down thereon.

55 60 In the construction illustrated in Figs. 2, 3 and 4 the blocks or bars O, P, rest on such bridge, and the pin block D, the plate d, and the bridge C are relatively associated to slightly raise the strings or wires

X, X. The attaching of the device to the 65 bridge C by the screw J, with the string passing over the blocks O, P, and under the steel pin or rod Q will result in prevention of any dropping of the bridge below that which suffices to straighten the wires or 70 strings: as further dropping will draw the device down therewith.

I have found that by forcing the strings or wires out of a horizontal plane, and associating the plate, pin block and bridge so that the 75 strings or wires are slightly higher at the point therein which passes over or through the device on the bridge than at the ends of such strings or wires, downward pressure of the strings and device on the bridge is obtained, and vibration of such strings or wires 80 is conducted through the blocks or bars O, P, and through the bridge C, to the sounding board to a greater extent than is otherwise done. 85

It will be observed that the bars O, Fig. 8, are, respectively, provided with rabbets U, U, such rabbets engaging with one end of the body part G. The strings of the instrument are forced down on the bars O, as hereinbefore described, and such strings tend to hold the end of the body part G which is within this rabbet, down on to the bridge C, particularly in the case of any loosening of the screw J: and the depth of the notch h' in the gear 90 g', relative to the bar P, is such that upon any loosening of screw J such strings will also hold such end of the body part G down on to the bridge. 95

Having thus described my invention, the 100 construction of a device embodying the same, and the operation thereof, what I claim as new and desire to secure by Letters Patent is;—

1. An agrafe comprising a sheet metal 105 blank formed up to obtain a base and sides, such base concaved on the under side thereof and provided with an aperture therethrough and with a projection forced out therefrom and such sides provided respectively with recesses, in combination with bars over which strings may extend, and a pin arranged to removably engage with the recesses and to force the strings on to the bars; substantially as described. 110

115 2. An agrafe comprising a sheet metal blank formed up to obtain a base and sides, such sides provided respectively with recesses, in combination with bars over which strings may extend, and a pin arranged to removably engage with the recesses and to force the strings on to the bars; substantially as described.

120 3. An agrafe comprising a sheet metal blank formed up to obtain a base and sides, such sides provided respectively with recesses, in combination with bars over which strings may extend and a pin, the bars and

pin respectively arranged to removably engage with corresponding recesses and the pin and bars relatively associated so that the pin will force the strings on to the bars; substantially as described.

4. An agraffe comprising a sheet metal blank formed up to obtain a base and sides, such base concave on the under side thereof and provided with an aperture therethrough and with a projection forced out therefrom and such sides provided respectively with recesses, in combination with bars over which strings may extend, and a pin, such bars and pin respectively arranged to removably engage with corresponding recesses and the bars and pin relatively associated to force the strings on to the bars; substantially as described.

5. An agraffe comprising a sheet metal blank formed up to obtain a base and sides and an end provided with notches such base concave on the under side thereof and provided with an aperture therethrough and with a projection forced out therefrom, and such sides provided respectively with recesses, in combination with a bar over which strings may extend, and a pin arranged to removably engage with the recesses and to

force the strings on to the bar; substantially as described.

6. An agraffe comprising a sheet metal blank formed up to obtain a base, sides and an end, such end provided with notches, such base concave on the under side thereof and provided with an aperture therethrough, and such sides provided respectively with recesses, in combination with a bar over which strings may extend, and a pin, such bar and the pin respectively arranged to removably engage with corresponding recesses on the sides, the bar and pin relatively associated to force the strings on the bar, and such bar provided with a rabbet to engage with one end of the base; substantially as described.

7. An agraffe comprising a sheet metal blank formed up to obtain a base, sides and an end, such end provided with notches and such sides respectively provided with recesses, in combination with a bar over which strings may extend, and a pin arranged to removably engage with the recesses to force the strings on the bar, substantially as described.

LEOPOLD AVISUS.

In the presence of—

CHARLES TURNER BROWN,
EDWARD J. BROWN.
